US0D1086018S

(12) **United States Design Patent** (10) **Patent No.:** **US D1,086,018 S**
(45) **Date of Patent:** **** Jul. 29, 2025**

(54) **BRACKET**

(71) Applicant: **Unirac, Inc.**, Albuquerque, NM (US)

(72) Inventors: **Todd Ganshaw**, Albuquerque, NM (US); **Ernest Gallegos**, Albuquerque, NM (US); **Sai Uppu**, Albuquerque, NM (US)

(73) Assignee: **Unirac, Inc.**, Albuquerque, NM (US)

(**) Term: **15 Years**

(21) Appl. No.: **29/977,853**

(22) Filed: **Dec. 10, 2024**

Related U.S. Application Data

(62) Division of application No. 29/898,143, filed on Jul. 24, 2023, now Pat. No. Des. 1,062,597, which is a division of application No. 29/865,299, filed on Jul. 18, 2022, now Pat. No. Des. 993,163, which is a division of application No. 29/700,579, filed on Aug. 2, 2019, now Pat. No. Des. 958,058.

(57) **CLAIM**

The ornamental design for a bracket, as shown and described.

DESCRIPTION

FIG. 1 is a perspective view of a bracket;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the bracket that form no part of the claimed design. The dot-dashed broken line represent a boundary of the claimed design and forms no part of the claimed design.

1 Claim, 7 Drawing Sheets
